REFRIGERATING APPARATUS OF THE
COMPRESSION TYPERudolf Hintze, Berlin-Charlottenburg, Germany;
vested in the Alien Property CustodianApplication February 26, 1941, Serial No. 380,596
In Germany January 12, 1940

8 Claims. (Cl. 62—116)

1

The present invention relates to improvements in refrigerating apparatus of the compression type.

In such apparatus two requirements must be fulfilled. On the one hand, it is desirable that the refrigerating apparatus be so designed as to enable a very rapid production of ice. This requirement can be met by employing refrigerants evaporating at low temperatures. On the other hand, the cooling chamber must be cooled by the evaporator, and for cooling purposes low temperatures are unfavorable, since the goods to be cooled become dry owing to the low temperatures.

The object of the present invention is to provide a cabinet refrigerator of the compression type which will meet the two above-mentioned requirements in a simple and effective manner. According to the invention, two refrigerants differing in specific weight and evaporating at different temperatures are employed in the apparatus. A separate evaporator is employed for each of the two refrigerants so that one evaporator may be chiefly employed for the rapid production of ice, whereas the other evaporator is above all designed as a cooler for the storage or cooling chamber. The two evaporators are preferably so arranged according to the invention that in operation the two refrigerants flow automatically into the respective evaporators. This can be attained by conveying the liquefied refrigerant from the condenser through a control member, at first to the evaporator in which the heavier refrigerant is used and thence through an overflow conduit to the second evaporator for the refrigerant of lower specific gravity. The heavier refrigerant of the refrigerant mixture flowing from the condenser into the evaporator collects in the lower part of the first evaporator vessel, whereas the refrigerant of lower specific gravity floats on the heavier refrigerant and flows into the second evaporator through the overflow conduit. The conduit connecting the two evaporators is preferably designed in the form of a liquid seal to ensure the withdrawal of vapors from each evaporator independently. The evaporator containing the refrigerant evaporating at a lower temperature is so designed that it may be employed for the production of ice, whereas the other evaporator is designed in the form of a chamber cooler. A particularly simple arrangement of the evaporators is obtained by arranging one evaporator within the other in such a manner that the inner evaporator serves to produce ice and the outer as a chamber cooler.

2

Further details of the invention will be apparent from the following description taken in connection with the accompanying drawing, in which

5 Fig. 1 shows a refrigerating apparatus of the compression type according to the invention, and

Fig. 2 is a schematic arrangement of the two evaporators within the cooling chamber of a refrigerator cabinet.

10 Referring to Fig. 1, 1 denotes the motor-compressor set. This set forces the refrigerant through a conduit 2 into an air-cooled condenser 3 where it is liquefied. The liquefied refrigerant then flows through a conduit 4 into a tank 5 housing a float-controlled valve 6. The tank 5 contains a mixture consisting of two refrigerants having different specific gravities. The mixture is supplied with the aid of the valve 6 to a collecting vessel or header 8 through a conduit 7, 15 evaporator conduits 9 being secured to the vessel 8 in any suitable manner. Since the refrigerant 11 has a lower specific gravity than the refrigerant 10, it floats in the vessel 8 on the surface of the refrigerant 10. Connected to the vessel 8 is 20 an overflow conduit 12 leading to a collecting vessel or header 13. The evaporator conduits 14 are secured to the vessel 13. In operation, the refrigerant of lower specific gravity passes into the evaporator 13, 14. The middle portion of the 25 conduit 12 is designed in the form of a liquid seal 16. The suction conduits 17 and 18 leading to the suction side of the compressor are connected to the vessels 8 and 13.

30 The refrigerant of higher specific gravity is employed in the evaporator 8, 9 designed in the form of a chamber cooler. To this end, as shown in Fig. 1, heat-radiating ribs 19 are so arranged as to be in heat contact with the refrigerant conduits 9. This evaporator 8, 9 contains a refrigerant, for instance SO_2 , which evaporates at a relatively high temperature. The evaporator 13, 14 is designed in the form of an ice-producing unit, as indicated schematically in Fig. 1 by an ice tray 20. A refrigerant, for instance CH_3Cl , 35 evaporating at a comparatively low temperature, is employed in the evaporator 13, 14.

40 According to Fig. 2, the evaporators 9 and 14 are arranged one within the other in such a manner that the evaporator 14, which serves to produce ice, is surrounded by the evaporator 9 serving mainly as a chamber cooler. As will be apparent from the temperatures indicated in Fig. 2, a natural temperature drop is attained due to the difference in temperature existing between 45 the outside atmosphere ($+30^\circ$), the cooling

chamber air ($+6^\circ$), the temperature (-2°) prevailing in the evaporator 9 serving as a chamber cooler, and the temperature (-15°) prevailing in the evaporator 14 serving for the production of ice.

What is claimed is:

1. A refrigerating apparatus having a refrigerant circulating system comprising a compressor, a condenser and two evaporators provided with headers, two refrigerating fluids in said circulating system, one having a higher specific gravity and boiling point than the other, the latter being adapted to float on the former, a conduit including a control valve connecting said condenser and the header of one of said evaporators, an overflow conduit connecting said header with the header of the second evaporator, separate conduits connecting each of said evaporators with the suction side of said compressor, the header of the first evaporator serving as a separating means for separating the two refrigerating fluids and for supplying the heavier one to the first evaporator and the lighter one to the second evaporator.

2. In a refrigerating apparatus as set forth in claim 1, the said overflow conduit being provided with a trap to form a liquid seal between the two evaporators.

3. Refrigerating apparatus of the compressor type, having a refrigerant circulation system containing two separable refrigerants, one having a higher specific gravity and boiling point than the other the latter being adapted to float on the former, comprising a compressor, a condensing means for condensing said refrigerants to obtain a liquid mixture thereof, two evaporators at least the first one of which is provided with a header, a conduit including a control means connecting said condensing means to the header of said first evaporator, an overflow conduit connecting the header of said first evaporator with the second of said evaporators, said header acting as a separating means for separating the said refrigerants and supplying the heavier one to the first evaporator and the lighter one to the second.

4. A refrigerating system as set forth in claim 3, in which the control means comprises a float valve for regulating the flow of the refrigerant

5 mixture from the condensing means to the separating header.

5. A refrigerating system as set forth in claim 3, in which the overflow conduit includes a trap to provide a liquid seal between the evaporators.

6. In a refrigerating system as set forth in claim 3, the evaporators each being connected to the suction side of said compressor by a separate conduit.

7. A cabinet refrigerator provided with a refrigerating apparatus of the compressor type, having a refrigerant circulating system containing two separable refrigerants, one having a higher specific gravity and boiling point than the other the latter being adapted to float on the former, comprising a compressor, a condensing means for condensing said refrigerants to obtain a liquid mixture thereof, two evaporators, at least the first one of which is provided with a header, a conduit including a control means connecting said condensing means to the header of said first evaporator, an overflow conduit connecting the header of said first evaporator with the second of said evaporators, said header acting as a separating means for separating the said refrigerants and supplying the heavier one to the first evaporator and the lighter one to the second, the second of said evaporators being designed for making ice and encompassed within the first.

8. A refrigerating apparatus having a refrigerant circulating system comprising a compressor, a condenser and two evaporators at least the first one of which is provided with a header, two separable refrigerating fluids in said circulating system one having a different specific gravity and boiling point than the other and one being adapted to float on the other, a conduit including a float valve connecting said condenser and the header of said first evaporator, an overflow conduit connecting said header with said second evaporator, separate conduits connecting each of said evaporators with the suction side of said compressor, the header of the first evaporator serving as a separating means for separating the two refrigerating fluids and for supplying the heavier one to the first evaporator and the lighter one to the second evaporator.
